Inventor
Daniel Schnabel,

By *Clarence A. O'Brien*, Attorney

UNITED STATES PATENT OFFICE

DANIEL SCHNABEL, OF MENNO, SOUTH DAKOTA

TAIL HOLDER

Application filed April 4, 1931. Serial No. 527,796.

This invention relates generally to an improvement in cow tail holders or the like, and relates particularly to a cow tail holder of new and novel structure and proportions, having advantages of operation and manufacture not heretofore exhibited in the art.

It is an object of this invention to provide a convenient and quickly and easily installable device of the character described which will release the tail of the animal in an emergency without injury thereto, and which may be suspended by any suitable means from the wall of a milking stall, or suspended upon a wire running through a barn and slidably thereon for convenient placement wherever desired.

These and other objects of the invention, its nature, and its composition and arrangement and combination of parts will be readily understood by any one acquainted with the art to which this invention relates upon consulting the following descriptions of the drawing, in which:—

Figure 1 is a general side elevational view 25 of my device partly in cross section.

Figure 2 is a side view of Figure 1.

Figure 3 is a horizontal cross sectional view through the upper part of Figure 1.

Referring in detail to the drawing, the numerals 5 and 6 refer respectively to each of a pair of wooden or other composition or material handled jaws having the straight uniform outward sides 7 and 8, respectively, and the concavities 9 and 10 in opposition, adapted to receive the tail of the animal therebetween, and the comparatively straight handle portions 11 and 12 rather widely and angularly spaced. The jaw structure 5 has a plate 13 centrally bent to provide journals 14 for a rectangularly bent wire or bar 15 which has one longitudinal side 16 journaled in the journaled portions 14 of the plate 13, and has the other longitudinal side thereof broken to provide a pair of inwardly directed spaced projections 17 adapted to enter and be anchored in the outward side 8 of the jaw structure 6, and bracing the same as seen in Figure 3. This arrangement pivots the jaw structures 5 and 6 just inwardly of the concavities 9 and 10.

Passed through a metal lined or other suitably constructed bore 18 in the jaw structure 6 is a wire or cord 19 which is tethered as at 20 in another bore 21 also transversely constructed in the jaw structure 5. The cord 19 is adapted to be suspended upon a nail or the like or to have a suitable means for carrying it upon a wire strung across the barn.

For imparting the requisite clamping action of the jaw structures 5 and 6 there is placed about or outwardly of the structure 15 a solid rubber band 22 adapted to be slipped inwardly and consequently stretched upon the tail gripping portions of the jaw structures 5 and 6. This rubber band is readily replaceable when worn out and provides a cheap and convenient tensioning means for the jaws.

It is to be definitely understood that I do not desire to limit the application of this invention to the particular modification set out herein to illustrate the principles thereof, and any change or changes may be made in material and structure consistent with the spirit and scope of the invention.

What is claimed is:—

1. A tail holder comprising a pair of jaw members having cooperating surfaces for engaging a tail, a hinge connection between the members whereby the members may be rocked upon one another for separating said cooperating surfaces for reception of a tail therebetween, closing means surrounding the members for normally maintaining said cooperating surfaces together, said hinge connection comprising a journal means mounted on the inward side of one member and a frame embracing the other member and having a portion journaled in said journal means whereby the inward side of the said other member is maintained rockably engaged with said journal means.

2. A tail holder comprising a pair of rockably related members having each on their meeting faces a curved protuberance, a rockable connection between the members comprising a journal means on the protuberance of one member and a frame embracing the other member adjacent its protuberance and having a portion journaled in said journal

member whereby the protuberance of the said other member rockably engages the journal means so as to condition easy and wide rocking of the members relative to each other; 5 and means surrounding the members at one side of said protuberances for urging one end of the members normally together for holding a tail therebetween, said means being adapted to permit said end of the members 10 to be yieldably separated by rocking the members.

3. A tail holder comprising a pair of rockably related members having each on one end a curved meeting face, a protuberance on 15 each member near its middle point, a rockable connection between the members connecting the protuberances, said connection comprising journal means on the protuberance of one member and a frame embracing 20 the other member adjacent its protuberance and having a portion journalled in said journal member whereby the protuberance of the said other member rockably engages the journal means so as to condition easy and wide 25 rocking of the members relative to each other, and means surrounding the curved meeting surfaces of the members for urging the curved faces together for holding a tail therebetween, said means being adapted to 30 yield to permit separation of the curved faces by rocking the members, and means for suspending the holder by both members thereof, comprising, a cord passed through an opening provided in the remaining end of one of 35 said members and anchored in a similar opening in the remaining end of the other of said members, whereby free rocking of the members is permitted while the holder is suspended.

40 4. A tail holder of the type described comprising a pair of handled tail-gripping members, opposed curved surfaces at one end of the members constituting tail-gripping jaws, connection means for rockably connecting 45 the members in side-by-side opposed relationship, said means comprising journal

means on the inner side of one member, and pivot means on the inner side of the other member received in said journal means, and constricting means surrounding the members and located between the connection means and the tail gripping jaws for urging the 75 jaws together.

5. A tail holder of the type described comprising a pair of handled tail-gripping members, opposed curved surfaces at one end of 75 the members constituting tail-gripping jaws, connection means for rockably connecting the members in side-by-side opposed relationship, said means comprising journal means on the inner side of one member, and pivot means on the inner side of the other member received in said journal means, and constricting means surrounding the members and located between the connection means and the tail gripping jaws for urging 80 the jaws together, and holder suspending means comprising a cord freely passed through an opening in one member and secured in an opening in the other member, whereby the holder may be suspended by 85 both members without interfering with the action of the tail-gripping members.

6. A tail holder comprising a pair of jaw members having near one end co-operating surface for clamping a tail therebetween, 95 connection means for rockably connecting the jaw members in opposed side-by-side relationship, said connection means comprising a frame embracing one jaw member, pivot means carried by the frame at the inner 100 side of the jaw members, journal means on the inner side of the other jaw member and receiving the pivot means, and contracting means embracing the jaw members and located between the connection means and the 105 end of the jaw members having the co-operating surfaces, whereby the last-mentioned end of the jaw members are resiliently urged together.

In testimony whereof I affix my signature. 110
DANIEL SCHNABEL.
